CLAIM

The ornamental design for an insert for an arthropod trapping device, as shown and described.

DESCRIPTION

FIG. 1 is a front, right-side isometric view of a first embodiment of an insert for an arthropod trapping device; FIG. 2 is a rear, left-side isometric view of the insert for an arthropod trapping device of FIG. 1; FIG. 3 is a front view of the insert for an arthropod trapping device of FIG. 1; FIG. 4 is a right side view of the insert for an arthropod trapping device of FIG. 1; FIG. 5 is a rear view of the insert for an arthropod trapping device of FIG. 1; FIG. 6 is a left side view of the insert for an arthropod trapping device of FIG. 1; FIG. 7 is a top view of the insert for an arthropod trapping device of FIG. 1; FIG. 8 is a bottom view of the insert for an arthropod trapping device of FIG. 1; FIG. 9 is a front, right-side isometric view of a second embodiment of an insert for an arthropod trapping device; FIG. 10 is a rear, left-side isometric view of the insert for an arthropod trapping device of FIG. 9; FIG. 11 is a front view of the insert for an arthropod trapping device of FIG. 9; FIG. 12 is a right side view of the insert for an arthropod trapping device of FIG. 9; FIG. 13 is a rear view of the insert for an arthropod trapping device of FIG. 9; FIG. 14 is a left side view of the insert for an arthropod trapping device of FIG. 9; FIG. 15 is a top view of the insert for an arthropod trapping device of FIG. 9; and, FIG. 16 is a bottom view of the insert for an arthropod trapping device of FIG. 9.

The broken lines illustrate structure or features that form no part of the claimed design.

The dot-dash broken lines define the bounds of the claimed design and form no part thereof.
